UNITED STATES PATENT OFFICE.

WALTER C. ELLSWORTH, OF NEW YORK, N. Y.

RIBBON OR TAPE NEEDLE.

1,351,418.

Specification of Letters Patent. Patented Aug. 31, 1920.

Application filed November 21, 1919. Serial No. 339,770.

To all whom it may concern:

Be it known that I, WALTER C. ELLSWORTH, a citizen of the United States, residing in the city of New York, county of New York, and State of New York, have invented certain new and useful Improvements in Ribbon or Tape Needles, of which the following is a full, clear, and exact description.

This invention relates to ribbon or tape needles; that is to needles for threading ribbon or tape through lace openwork, narrow hems of garments and for similar uses.

The type of needle or bodkin commonly used heretofore for the purpose above indicated is provided with rather blunt ends and adjacent one of these ends is provided a relatively large eye through which the tape or narrow ribbon may be threaded. In order to use this type of needle, the desired piece of ribbon or tape is threaded through the eye of the needle and then the needle is inserted through the opening in the lace work or through the hem of a garment while the ribbon or tape is pulled along by the needle. This type of needle or bodkin is open to the objection that it not only is more or less difficult to thread, but that it crushes and creases the portion of ribbon drawn through the eye of the needle, and by folding back the ribbon at the eye a bulk is formed at this point which retards the forward movement of the bodkin. Furthermore, this type of needle often becomes accidentally unthreaded while being used, which is annoying and wastes time.

The primary object of my invention is to provide a ribbon or tape needle which is free from the objections above pointed out, more particularly the primary object of my invention is to provide a ribbon or tape needle with conveniently operable means upon one end of the same for firmly gripping an end of the tape or ribbon which is to be threaded through a garment or the like.

Another object of my invention is to provide a needle of the type above indicated with gripping jaws which may be opened to engage or release the tape by simply squeezing slightly an intermediate portion of the needle.

To these and other ends the invention consists in the novel features and combinations of parts to be hereinafter described and claimed.

55 In the accompanying drawing:

Figure 1 is a side view of a person's hand

showing my needle held between the finger and thumb with an intermediate portion of the needle compressed to open the jaws of the same.

Fig. 2 is an enlarged edge view of the needle shown in Fig. 1.

Fig. 3 is a side view of Fig. 2.

Fig. 4 is an enlarged end view of the needle, as shown in Fig. 1, the teeth of the needle being shown spaced apart.

Fig. 5 is a view similar to Fig. 3, but showing a tape or ribbon held between the jaws of the needle; and

Fig. 6 is a view similar to Fig. 2, but showing a slight modification of my invention.

The ribbon or tape needle disclosed in the drawing is preferably constructed of a pair of relatively long narrow resilient blades 10 and 11 firmly secured together at the forward end of the needle, as indicated by 12. The rear end of each of the blades 10 and 11 are bent toward each other to form the jaws 13 and 14, and these jaws are preferably provided with the interengaging saw-teeth 15 and 16, as shown in Fig. 4. The blades 10 and 11, which are preferably constructed of resilient steel operate to normally retain the jaws 13 and 14 in gripping engagement with each other, so that after a piece of tape or ribbon 17 has been inserted between these jaws, as shown in Fig. 5, the resiliency of the blades 10 and 11 will retain the jaws 13 and 14 in firm gripping engagement with the ribbon or tape.

In order to provide means by which the jaws 13 and 14 may be conveniently disengaged from each other in order that a piece of tape may be inserted between the same or removed therefrom, an intermediate portion of the blades 10 and 11 are preferably spaced from each other, as shown in Figs. 2 and 5, and adjacent the rear end of the needle are formed the inwardly extending ribs or abutments 18 and 19. These ribs or abutments are positioned opposite each other, and under normal conditions lie a very short distance apart, the arrangement being such that these abutments will not interfere with the normal gripping operation of the jaws 13 and 14, but when it is desired to separate these jaws, all that is necessary is to compress an intermediate portion of the blades 10 and 11, as shown in Fig. 1, whereupon the abutments 18 and 19 will be brought into engagement with each

other and will serve as fulcrums about which the jaws 13 and 14 will swing away from each other, as clearly shown in Fig. 1. While the jaws are held open in the manner just pointed out, the ribbon or tape may be easily inserted between the same, whereupon the pressure is removed from the intermediate portion of the blades, so that the parts may return to their normal position.

The device shown in Fig. 6 differs from the device shown in Figs. 1 to 5 inclusive, only in that the blades 10' and 11' are shown as constructed of one integral piece of metal with the parts bent back upon themselves at the forward end of the needle, as indicated by 20, whereas in Figs. 1 to 5 inclusive, the blades 10 and 11 are made of separate pieces of steel, which may be secured together by solder or by any other preferred means.

From the above description when read in connection with the drawing, it will be seen that my ribbon or tape needle may be very easily attached to the ribbon or tape preparatory to threading the same through the openings in a garment or piece of cloth, and that when this needle is once engaged with a piece of ribbon or tape, it is practically impossible for the same to become accidentally unfastened from this needle, while when it is desired to release the ribbon or tape from my needle, all that is necessary is simply to squeeze an intermediate portion of the blades 10 and 11 to open the jaws, as shown in Fig. 1.

It will be apparent that minor changes may be made in the device herein disclosed without departing from the scope of my invention as defined in the annexed claims.

What I claim is:

1. A ribbon or tape needle consisting of a pair of resilient blades secured together and provided with interengaging teeth being turned out of the planes of the blades to oppose each other and at one end of said needle, said teeth normally held in engagement with each other by the resiliency of said blades.
2. A ribbon or tape needle consisting of a pair of resilient blades secured together at one end and having an intermediate part spaced from each other, said blades provided with interengaging jaws at the opposite end of said needle, and coöperating abutments formed upon said blades adjacent said jaws, said abutments constructed to

serve as fulcrums about which said jaws swing away from each other when an intermediate portion of said needle is compressed.

3. A ribbon or tape needle consisting of a pair of resilient blades secured to each other with an intermediate portion thereof spaced apart, said blades provided with coöperating teeth normally held in engagement with each other by the resiliency of said blades, and means for separating said teeth comprising inwardly extending abutments positioned to engage each other and to serve as fulcrums about which said teeth move away from each other when the intermediate portion of said needle is compressed.

4. A tape needle consisting of a pair of resilient blades secured to each other with an intermediate portion thereof spaced apart, said blades provided with coöperating jaws, and means for forcing said jaws apart comprising abutting surfaces between said blades positioned to engage each other and to serve as fulcrums about which said jaws move away from each other when the intermediate portion of said needle is compressed.

5. A ribbon or tape needle consisting of a pair of substantially parallel resilient blades secured together, each of said blades provided with tape engaging teeth turned out of the planes of the blades to oppose each other and normally held in contact with each other by the resiliency of said blades.

6. A ribbon or tape needle consisting of a pair of resilient blades secured together and provided with tape engaging parts normally held in gripping engagement with each other by the resiliency of said blades, and a fulcrum positioned between said blades and constructed to force said tape engaging parts out of engagement with each other when portions of said blades are pressed toward each other.

7. A tape needle, comprising two substantially parallel resilient blades, having turned portions at the ends thereof, each of said turned portions being provided with teeth facing the teeth of the other turned portion, said teeth being normally held in gripping engagement by the resiliency of the blades.

In witness whereof, I have hereunto set my hand on the 18th day of November, 1919.

WALTER C. ELLSWORTH.
